UNITED STATES PATENT OFFICE.

EDDIE C. WILLIAMS, OF BANKS, ALABAMA, ASSIGNOR OF ONE-HALF TO JOSEPH THOMAS REYNOLDS, OF BANKS, ALABAMA.

AERIAL BOMB.

1,359,009.

Specification of Letters Patent. Patented Nov. 16, 1920.

Application filed November 1, 1919. Serial No. 334,987.

To all whom it may concern:

Be it known that I, EDDIE C. WILLIAMS, a citizen of the United States, residing at Banks, in the county of Pike and State of 5 Alabama, have invented certain new and useful Improvements in Aerial Bombs, of which the following is a specification.

This invention relates to improvements in aerial bombs, and more particularly to 10 the firing means therefor.

An important object of this invention is to provide a bomb having novel means whereby the same is caused to explode upon striking the ground or a building.

15 A further object of the invention is to provide an aerial bomb provided with a novel form of safety pin to prevent the device from accidentally firing while being handled.

20 A further object of this invention is to provide an aerial bomb which is of highly simplified construction, simple to assemble and cheap to manufacture.

Other objects and advantages of the 25 invention will be apparent during the course of the following description.

In the accompanying drawings forming a part of this application, and in which like numerals are employed to designate like

30 parts throughout the same,

Figure 1 is a perspective of the improved bomb;

Fig. 2 is a horizontal section taken on line 2-2 of Fig. 1;

35 Fig. 3 is a perspective of the firing pin;

Fig. 4 is a central vertical section through the bomb;

Fig. 5 is a fragmentary section through the bomb set for use;

40 Fig. 6 is a detail perspective of a supporting device for the powder case or shell.

In the drawings wherein for the purpose of illustration is shown a preferred embodiment of the invention, the numeral 10 design-

45 nates a casing of the bomb having its upper end provided with a closure 11. The closure 11 is provided with a depending interiorly screw threaded annular flange 12 having threaded engagement with the exterior of

50 the casing 10. The closure 11 is provided with a pivot pin 12 which rotatably supports a fan 13 adapted to maintain the vertical position of the bomb during its de-

scent. As is obvious from Fig. 1, the guiding propeller or fan is rotated during the 55 descent to the ground and thereby maintains the equilibrium of the bomb.

As illustrated in Fig. 4, the bottom portion of the case 10 is provided with an annular disk 14 adapted for supporting a 60 quantity of shrapnel 15.

The powder shell 16 is arranged centrally within the casing and is entirely surrounded by the shrapnel, whereby when the powder 65 17 within the shell 16 explodes the shrapnel will be blown in all directions. In positioning the shell 16, the cap 19 of the same is snugly arranged within a central opening 18 in the disk 14 and the cap 19 is thereby firmly held in position so as to aline the 70 percussion cap 20 of the same with a firing pin 21. As is usual in bombs, the percussion cap 20 is provided with a detonator 22 having connection with a fuse 23 which is adapted to set off the powder 17. 75

As illustrated in detail in Fig. 6, the cap 19 is held within the opening 18 by a lever 24 pivoted in one side wall of the opening as indicated at 25. Before the cap 19 has been positioned the lever is lowered and its 80 forward portion is secured within a slot 26 in the opposite side wall.

A concavo-convex firing pin support 27 has threaded engagement with a depending annular flange 28 formed on the lower end 85 of the casing 10. The concavo-convex firing pin support is provided with a centrally arranged opening 29 which slidably receives the firing pin 21. The upper end portion of the firing pin is passed through the centrally arranged opening 30 in a guide or tensioning disk 31, a coil spring 32 surrounding the pin 21 engages a retaining pin 33 carried by the lower portion of the firing pin and is adapted to normally retain the 90 pointed end portion of the firing pin spaced from the percussion cap. As illustrated in Fig. 4, the disk 31 has threaded engagement with the inner side of the concavo-convex firing pin support as indicated at 34 and is 100 adapted to be adjusted for properly tensioning the coil spring 32. If it is desired to put considerable tension on the firing pin 21, the disk 31 is arranged in the lower portion of the firing pin support 27. A sleeve 35 is 105 carried by the disk 31 and surrounds the

coil spring 32 and an annular shoulder 36 carried by the inner side of the support 27. It is thus apparent that the disk 31 serves the double function of adjusting the tension 5 of the coil spring 32 and guiding the firing pin 21.

The firing pin 21 is provided with a concavo-convex ground contact head 37, having approximately the same curvature as the 10 support 27. As illustrated in several figures the concavo-convex contact head 37 is of a diameter slightly less than the diameter of the casing 10 and is adapted for affording a comparatively large contact surface upon 15 engagement with the ground. In providing a relatively large contact member the firing of the device upon striking the ground is assured, also the bomb is prevented from entering the ground before firing.

20 As illustrated in detail in Fig. 3, the firing pin is provided with a transverse slot 37 adapted to receive a safety lever or pin 38. As is obvious, the safety device 38 is adapted to prevent the accidental movement 25 of the pin 21 as the result of the accidental striking of the firing head 37 while the device is being handled. The lever 38 terminates short of the outer edge of the firing head 37 and is adapted to be manually re- 30 moved prior to dropping the bomb. When the member 38 is removed the firing pin 21 is free to be moved inwardly for engaging the percussion cap 20 whereby the bomb may be exploded.

35 In assembling the device, the shrapnel and the shell are arranged within the casing and the lever 24 is positioned to secure the shell cap 19 in position and prevent the same from dropping onto the firing pin 40 and accidentally setting off the bomb. The firing pin and the spring therefor is positioned prior to applying the support 27 of the bomb. When the spring 32 has been properly tensioned by the disk 31, the support 27 is screwed into the annular flange 45 28 and the device is then ready for use.

When it is desired to drop the bomb from an airplane or other elevated point, the safety device 38 is removed in order that 50 the pin 21 may engage the percussion cap 20 when the bomb strikes the ground or a building.

It is to be understood that the form of the invention herewith shown and described is 55 to be taken as a preferred embodiment of the same and that such minor changes in arrangement and the construction of parts may be made as will remain within the spirit of the invention and the scope of 60 what is claimed.

Having thus described the invention, what is claimed as new is:

1. A bomb including a casing having a depending screw threaded flange, a firing 65 pin support threaded onto said flange and

having a centrally arranged opening, a tensioning device arranged within said firing pin support and having a centrally arranged opening, a firing pin extending through the openings in said firing pin support and said 70 tensioning device, a coil spring arranged between said tensioning device and the lower end of said firing pin support, and an enlarged contact head on said firing pin.

2. A bomb including a casing having a 75 bottom wall provided with an opening, a powder shell having a cap arranged within said opening, a pivoted lever traversing said opening and supporting the said cap, the forward portion of said lever being engaged 80 with the side wall of said opening, and a firing pin arranged in spaced relation to said cap.

3. A bomb including a casing having a 85 bottom wall provided with an opening, a powder shell having a cap arranged within said opening, a lever pivoted to one side wall of the opening and having its free end portion engaged with the opposite side wall of the opening, said lever being adapted for 90 supporting said cap, a firing pin for said cap, means to support said firing pin, and a spring for normally spacing said firing pin from said cap.

4. A bomb including a casing having an 95 attaching flange, a concavo-convex firing pin support detachably connected to said flange and having an opening, a firing pin extending through said opening, a combined firing pin guide and tensioning device 100 adjustable within said firing pin support, a spring confined between said tensioning device and the rear end portion of said firing pin, and a safety device associated with said firing pin, said firing pin being provided 105 with a contact head.

5. A bomb including a casing, a concavo-convex firing pin support detachably connected to said casing, a detonator arranged within said casing, a firing pin carried by 110 said concavo-convex firing pin support, and means to normally retain said firing pin in spaced relation to said detonator, said firing pin being provided with an enlarged concavo-convex contact head, arranged directly beneath said concavo-convex firing pin support and approximately conforming 115 to the curvature of the same.

6. A bomb including a casing, a firing pin support carried by said casing, a firing pin 120 extended through said firing pin support, a tensioning disk adjustable within said firing pin support, a spring confined between said tensioning disk and the rear end portion of said firing pin, the inner side of said 125 firing pin support being provided with an annular shoulder surrounding said firing pin, and a sleeve carried by said tensioning disk and surrounding said spring and said annular shoulder.

7. A bomb including a casing, a detonator carried by the casing, a firing pin support detachably connected to said casing and provided with an opening, a firing pin 5 extended through said opening, the outer end portion of said firing pin being provided with a transverse slot, a safety device ar-

ranged within said slot, and an enlarged head formed on the outer end of said firing pin and extending beyond said safety device, for protecting the same. 10

In testimony whereof I affix my signature.

EDDIE C. WILLIAMS. [L.S.]
